US0D1071497S

(12) United States Design Patent (10) Patent No.: US D1,071,497 S
(45) Date of Patent: * Apr. 22, 2025

(54) SHOE

(71) Applicant: Bottega Veneta S.R.L., Montebello Vicentino (IT)

(72) Inventor: Matthieu Blazy, Milan (IT)

(73) Assignee: BOTTEGA VENETA S.R.L., Montebello Vicentino (IT)

() Term: 15 Years

(21) Appl. No.: 29/907,396

(22) Filed: Jan. 5, 2024

(30) Foreign Application Priority Data

Jul. 19, 2023 (EM) 015028555-0002

(51) LOC (15) Cl. 02-04

(52) U.S. Cl.

USPC D2/910; D2/957; D2/959

(58) Field of Classification Search

USPC D2/896, 900-902, 907-912, 919-924, D2/925-945, 946-961, 969-978
